these unsaturated esters yield compounds containing three phosphorus atoms.

We claim:

1. A process for the preparation of bis(3-dialkylphosphonopropyl) esters of the general formula

wherein n is an integer from 0 to 8 and R is an alkyl radical comprising the free radical addition of a dialkyl phosphonate to a diallyl ester of a saturated aliphatic dibasic acid having 2 to 10 carbon atoms.

2. The process of claim 1 in which the free radical addition of a dialkyl phosphonate is initiated by adding 25 t-butyl perbenzoate and heating the mixture to about 100° C.

3. The process of claim 1 wherein n is 8 and R is an ethyl radical.

4. The process of claim 1 wherein n is 7 and R is a butyl radical.

5. The process of claim 1 wherein n is 4 and R is a butyl radical.

6. The process of claim 1 wherein n is 4 and R is a 2-ethyl hexyl radical.

38 7. The process of claim 1 wherein n is 2 and R is a butyl radical.
